[57] CLAIM

The ornamental design for the bicycle light, as shown and described.

DESCRIPTION

FIG. 1 is a front perspective view of a bicycle light showing the new design;

FIG. 2 is a rear perspective view of the bicycle light showing the new design;

FIG. 3 is a top view of the bicycle light;

FIG. 4 is a side view of the bicycle light;

The other side of the bicycle light is a mirror image of the FIG. 4;

FIG. 5 is a bottom view of the one side of the bicycle light;

FIG. 6 is a front view of the bicycle light;

FIG. 7 is a rear view of the bicycle light;

FIG. 8 is a front perspective view of a second embodiment thereof;

FIG. 9 is a rear elevational view of the bicycle light and bracket;

FIG. 10 is a top view of the bicycle light and bracket;

FIG. 11 is a side view of the bicycle light and bracket;

The other side of the bicycle light and bracket is a mirror image of FIG. 4A;

FIG. 12 is a bottom view of the bicycle light and bracket;

FIG. 13 is a front view of the bicycle light and bracket; and,

FIG. 14 is a rear view of the bicycle light and bracket.
